CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

1,280,714.

Specification of Letters Patent

Patented Oct. 8, 1918.

Application filed March 29, 1917. Serial No. 158,198.

To all whom it may concern:

Be it known that I, CHARLES L. GOODRUM, a citizen of the United States, residing at New York, in the county of New York and 5 State of New York, have invented certain new and useful Improvements in Telephone Systems, of which the following is a full, clear, concise, and exact description.

This invention relates to improvements in 10 telephone systems, and more particularly to improvements in systems employing machine switching.

It is well known that the magneto telephone receiver transmits voice currents with 15 clearness and accuracy, and without the distortion which arises when the microphone is employed as part of the telephone equipment. However, when the magneto telephone receiver is employed to generate voice 20 currents, these currents are so minute that the diaphragm of the receiver of the listening party is actuated so gently that the message is scarcely audible. As regards transmission, the use of the magneto telephone is 25 particularly advantageous, since the voice currents are so minute that difficulty from crosstalk is minimized and conductors of a much smaller size may be employed.

In order to utilize the magneto telephone 30 receiver in the transmission of the voice currents, it is proposed to utilize means to amplify the minute voice currents so that the message transmitted will be clearly heard by the listening party.

Figure 1 of the drawings diagrammatically represents a portion of a telephone system employing the present invention. The line finder, or other switch, employed to locate the calling line and the selector 40 switches for extending the calling line to a final or connecting switch, are merely indicated in this disclosure, and may be of any desired construction. The portion of Fig. 1, included within the dotted line inclosure, 45 represents the so-called "mechanical repeater" and a circuit arrangement associated therewith, which co-operates therewith to amplify the voice currents transmitted over the established connection.

Fig. 2 diagrammatically represents a modified form of the invention in which a vacuum tube relay of the audion type is modified instead of the "mechanical repeater." When the apparatus and circuits,

shown in Fig. 2, are substituted for the corresponding elements, included within the dotted line inclosure of Fig. 1, the arrangement by which a vacuum tube relay may be employed to amplify voice currents in an audion telephone system, will be shown.

The substation set employed in this system consists of a dial switch 1 of any preferred form, and a combined transmitter and receiver. This combined transmitter and receiver is provided with a permanent magnet 2, near one end of which there is provided a coil in series with the talking circuit. This permanent magnet operates in the well-known manner to actuate a diaphragm 3. The subscriber speaks into the 70 mouthpiece 4 and actuates the diaphragm 3, as in the magneto telephone receiver. The subscriber receives the message through the earpiece 5.

It is believed that the operation of the 75 system will best be understood by describing the establishment of a connection from a calling subscriber whose substation is indicated at A, to a called subscriber whose substation is diagrammatically shown at B.

When the calling subscriber at substation A removes his transmitter and receiver from the switchhook 6, a line finder, indicated by the brushes 13, 14 and 15, operates in the well-known manner to locate the terminals 16, 17 and 18 of the calling line. The operation of the line finder serves to extend the calling line to an idle first selector and in turn to the proper connector. As soon as the calling line has been extended to the 90 connector, the line relay 32 is energized over a circuit extending from battery, left-hand winding of relay 32, terminal 29, brush 23 of the selector, brush 13 and terminal 16 of the line finder, contacts of the substation impulse sender 1, through the substation circuit, terminal 17 and brush 14 of the line finder, brush 24 and terminal 30 of the selector, right-hand winding of relay 32, back to battery. The line relay 32 attracts its 100 armature and completes an energizing circuit for the slow-releasing relay 33, which circuit is traceable from grounded battery, winding of relay 33, front contact and armature of relay 32, to ground. It will 105 be understood that the relay 33 is slow to release and therefore does not retract its armatures during momentary interruptions

of its energizing circuit, such as the interruptions resulting from the operation of the line relay in response to dial impulses. The relay 33 attracts its armatures and at its 5 right-hand armature and front contact closes a break point in the operating circuit of the stepping magnet 34, and the slow releasing relay 40. At the left-hand back contact and armature of relay 33 a break 10 point in the circuit of the release magnet 54 of the switch is opened. In response to the operation of the dial switch 1 the line relay 32 vibrates its armature. At each retraction of the armature of relay 32 a circuit 15 is completed from ground, armature and back contact of this relay, right-hand armature and front contact of relay 33, conductor 35, side-switch wiper 36 in its first position, winding of primary stepping magnet 34, to grounded battery. In response to 20 the tens series of impulses, the connector switch operates to place its brushes 37, 38 and 39 opposite the group of lines in which the called line terminates. As soon as the 25 relay 33 attracted its armature and upon the first retraction of relay 32 a circuit was completed from ground, armature and back contact of relay 32, right-hand front contact and armature of relay 33, winding of slow-releasing relay 40, to grounded battery. 30 The relay 40 attracts its armatures and at its right-hand armature and contact completes an energizing circuit for escape magnet 41, which circuit is completed from 35 grounded battery, winding of relay 41, right-hand front contact and armature of relay 40, back contact and armature of ringing trip relay 42, to ground. The escape magnet 41 is energized in this circuit.

40 At the close of the tens series of impulses, the line relay 32 attracts its armature for a relatively long interval which interrupts at its armature and back contact the operating circuit of the relay 40 for a 45 sufficiently long period to permit this relay to deenergize. Upon the deenergization of the relay 40 the escape magnet 41 deenergizes and moves the side-switch wipers into their second position.

50 In the second position of the side-switch wipers, in response to the units series of impulses, the line relay 32 again vibrates its armatures and again causes the energization of relay 40 and the consequent energization 55 of the escape magnet 41. In response to this series of impulses the secondary stepping magnet 43 is operated over a circuit extending from grounded battery, winding of this magnet, side-switch wiper 36 in its second 60 position, conductor 35, right-hand front contact and armature of relay 33, back contact and armature of line relay 32, to ground. As a result of the operation of the secondary stepping magnet 43, the brushes 65 37, 38 and 39 of the connector are moved

into engagement with the terminals 44, 45 and 46 of the called line.

If the called line is idle when the relay 40 retracts its armatures, the energizing circuit of the escape magnet 41 is interrupted, causing this magnet to move the side-switch wipers into their third position. In position 3 of the side-switch wipers the relay 40 is energized over a circuit traceable from grounded battery, winding of relay 40, conductor 35, side-switch wiper 36, in its third position, conductors 47 and 62, front contact and armature of relay 32, to ground. Relay 40 in energizing causes escape magnet 41 to attract its armatures. A circuit 75 is now completed from grounded battery, winding of relay 40, conductor 35, side-switch wiper 36 in its third position, conductor 47, side-switch wiper 48, connector brush 37, and terminal 44 of the called line, through 80 the substation circuit at B, terminal 45 of the called line, connector brush 38, side-switch wiper 49 in its third position, conductor 50, armature and front contact of escape magnet 41, winding of a ringing trip 85 relay 42, to the source of high-frequency signaling current 51. The high-frequency signaling current is applied to the calling line and operates the diaphragm of the receiver in the same manner as a "howler." 90

When the called subscriber at the substation removes his receiver from its switchhook, the ringing trip relay 42, which is marginal, is energized and at its armature and back contact interrupts the energizing 100 circuit of the escape magnet 41 to move the side-switch wipers into their fourth or talking position.

When the side-switch wipers 58, 59, 60 and 61 are moved into their fourth position, a 105 current amplifier, which may be of the type disclosed in the patent to Colpitts, No. 1,200,082, October 3, 1916, is connected to the talking trunk which interconnects the calling and called substations. 110

The primary winding 7 of the repeater coil 8 is bridged across the conductors of the trunk interconnecting the substations A and B. The secondary winding of the repeater coil 8 leads to the actuating winding 115 10 of a telephone repeater of the receiver microphone type. Telephonic currents, therefore, coming in from a telephone station A over the selected trunk will flow through the winding 10 of the repeater and actuate 120 the microphone elements 12, thereby sending out amplifying telephone currents through the windings 21 of the output transformer 20, whose secondary windings are included in series with the conductors of the trunk 125 leading to the substation B.

If, however, the desired line is busy as a called line, ground will be applied to the test terminal 46 through a side-switch wiper similar to 52 in its fourth position through 130

agreement to within the terminus of the
calculated instabilities.

What is claimed:

11. Clinical decision support system

1. The above principle is, so far, a very simple one, but it is not yet complete. It is necessary to provide for changing the incoming line, a plurality of outgoing lines, automation to switch the interconnecting switch incoming line with any of said outgoing lines, means associated with said incoming line and with each of said outgoing lines for generating video currents, and means at said telephone exchange for amplifying said video currents.

29. In a telephone system, an telephone exchange, an incoming line, a plurality of outgoing lines, an automatic switch from incoming, said incoming line with any of said outgoing lines, means associated with said incoming line and with each of said outgoing lines for generating voice currents, and means at said telephone exchange for amplifying, said voice currents, said means being connected from said incoming line.

33. In a telephone system, an telephone exchange having main incoming lines, auxiliary outgoing lines, an automatic switch for interconnecting said incoming lines with any of said outgoing lines to extend a talking circuit, means associated with said incoming lines and with each of said outgoing lines for generating voice currents, and means at said telephone exchange for amplifying said voice currents, said means being connected to said talking circuit.

44. In a telephone system, an incoming line, a plurality of outgoing lines, an automatic switch to interconnecting said incoming line with any of said outgoing lines to extend an existing circuit, means associated with said incoming line and with each of said outgoing lines for generating voice currents, and means for amplifying said voice currents, said means being connected to said talking circuit by said automatic switch in its operation.

11
makes good that any video carrying increases, such as a vacuum tube medium type, may be used without loss of mechanical regulation. 11
A vacuum tube relay and resistors are diaphragmatically shown to will be destroyed but this is not limited to the form of 11
relay or the arrangement of 11
circuits for the same. It can be shown that different arrangements 11
vacuum tube relay suitable 11
65. One at telephone system, having incoming lines, 11
a plurality of outgoing lines, and automatic switches 11
for interconnecting said incoming lines with any of said outgoing lines to extend and taking current, said automatic switches including an auxiliary switch, means associated with said incoming lines and with each of said outgoing lines for generating video currents, and means for amplifying said video currents, said means being connected to said outgoing lines by said auxiliary switch.

36.11 Hand telephone system, and incoming lines, a plurality of outgoing lines, an automatic switch from interconnecting said incoming lines with any of said outgoing lines, means associated with said interconnecting lines and with each of said outgoing lines for generating and receiving voice currents, and an electronic amplifier for amplifying said voice currents.

7. In a telephone system, an incoming line, a plurality of outgoing lines, an automatic switch for interconnecting said incoming line with any of said outgoing lines, means associated with said incoming line and with each of said outgoing lines for generating and receiving voice currents, and a thermionic amplifier for amplifying said voice currents, said amplifier being connected to said incoming line. 55
8. In a telephone system, an incoming line, a plurality of outgoing lines, an automatic switch for interconnecting said incoming line with any of said outgoing lines to extend a talking circuit, means associated with said incoming line and with each of said outgoing lines for generating and receiving voice currents, and a thermionic amplifier for amplifying said voice currents, said thermionic amplifier being connected to said talking circuit. 60
9. In a telephone system, an incoming line, a plurality of outgoing lines, an automatic switch for interconnecting said incoming line with any of said outgoing lines to extend a talking circuit, means associated with said incoming line and with each of said outgoing lines for generating and receiving voice currents, and a thermionic amplifier for amplifying said voice currents, said thermionic amplifier being connected to said talking circuit by said automatic switch in its operation. 70
10. In a telephone exchange system, an incoming line, a plurality of outgoing lines, an automatic switch for interconnecting said incoming line with any of said outgoing lines to extend a talking circuit, said automatic switch being provided with an auxiliary switch, means associated with said incoming line and with each of said outgoing lines for generating and receiving voice currents, and a thermionic amplifier for amplifying said voice currents, said thermionic amplifier being connected to said talking circuit by said auxiliary switch. 75
11. In a telephone system, a telephone exchange, an incoming line, a plurality of outgoing lines, an automatic switch for interconnecting said incoming line with any of said outgoing lines, means associated with said incoming line and with each of said outgoing lines for generating and receiving voice currents, and a thermionic amplifier for amplifying said voice currents, said thermionic amplifier at said telephone exchange for amplifying said voice currents. 80
12. In a telephone system, a telephone exchange, an incoming line, a plurality of outgoing lines, an automatic switch for interconnecting said incoming line with any of said outgoing lines to extend a talking circuit, means associated with said incoming line and with each of said outgoing lines for generating and receiving voice currents, and a thermionic amplifier at said telephone exchange for amplifying said voice currents, said thermionic amplifier being connected to said talking circuit. 85
13. In a telephone system, a telephone exchange, an incoming line, a plurality of outgoing lines, an automatic switch for interconnecting said incoming line with any of said outgoing lines to extend a talking circuit, means associated with said incoming line and with each of said outgoing lines for generating and receiving voice currents, and a thermionic amplifier at said telephone exchange for amplifying said voice currents, said thermionic amplifier being connected to said talking circuit by said automatic switch in its operation. 90
14. In a telephone system, subscribers' lines each provided with a device for receiving and transmitting voice currents, automatic means for interconnecting said subscribers' lines, and means common to a plurality of said lines for amplifying said voice currents. 95
15. In a telephone system, subscribers' lines each provided with a device of constant impedance for receiving and transmitting voice currents, automatic means for interconnecting said subscribers' lines, and means common to a plurality of said lines for amplifying said voice currents. 100
16. In a telephone system, subscribers' lines each provided with a device having constant electrical characteristics for receiving and transmitting voice currents, automatic means for interconnecting said subscribers' lines, and means common to a plurality of said lines for amplifying said voice currents. 105

In witness whereof, I hereunto subscribe my name this 27th day of March, A. D. 1917.

CHARLES L. GOODRUM.
